MICROWAVE AMPLIFIER OF THE MAGNETRON TYPE

Filed June 25, 1949

UNITED STATES PATENT OFFICE

2,640,951

MICROWAVE AMPLIFIER OF THE MAGNETRON TYPE

James Brown Horner Kuper, Bayport, N. Y., assignor to International Standard Electric Corporation, New York, N. Y., a corporation of Delaware

Application June 25, 1949, Serial No. 101,421

5 Claims. (Cl. 315—40)

1

This invention relates to electron discharge devices and is particularly directed to devices of the magnetron type. More specifically this invention is directed to devices which have some of the structural features of a magnetron but which are adapted to amplify energy in the frequency ranges of the magnetron oscillator.

It is well known that magnetrons of the multi-segment type are remarkably efficient generators of power in the micro-wave range, efficiencies as high as 50 to 70 percent being common in the 10 to 3 centimeter band. Part of such high efficiencies must be ascribed to the fact that any one electron or group of electrons interact with the electromagnetic field for a comparatively long time, several radio frequency cycles being usual. This is to be contrasted with the klystron type generator where the interaction time between the electrons of a beam and the radio frequency field is of the order of one half cycle or less.

The object of this invention is an amplifier in which the high electronic efficiency of the magnetron generator is utilized.

A more general object of this invention is an amplifier of high efficiency in the microwave range.

The amplifier according to this invention comprises an elongated tubular cathode coaxial with a tubular anode structure of equal length. In addition to the radial electric and axial magnetic fields for circularly gyrating the electrons there is provided an axial electric field to spiral the electrons about the cathode and lengthwise thereof. In the anode structure are a series of cavity resonators and slots disposed along a spiral line opposite and coextensive with the electron spiral path. Input and output antennae are coupled into resonators, respectively, at opposite ends of the anode structure.

The above-mentioned and other features and objects of this invention and the manner of attaining them will become more apparent and the invention itself will be best understood by reference to the following description of an embodiment of the invention taken in conjunction with the accompanying drawings, wherein: Figure 1 shows partly in longitudinal section a magnetron type amplifier structure in accordance with this invention; and Figure 2 is a transverse sectional view of Figure 1 taken along the line 2—2.

The conventional multicavity magnetron comprises a symmetrical electron interaction space between a tubular cathode and anode with a number of cavity resonators opening on the space,

2

and electric and magnetic fields of the proper magnitudes and directions to produce, according to one conception, traveling space charges or electron bunches which travel through the electric radio frequency fields at the cavity openings. Fortunately, the mean electrons entrain in the proper phase relation with the radio frequency field to yield as much as 50 to 70 percent of the kinetic energy, derived from the direct current field, to the radio frequency field. All of this radio frequency energy, minus the energy losses of the system, may be removed and utilized.

As in all generators, self-sustained oscillations require sufficient radio frequency energy to be fed back from one point in the system to another; for a given transconductance, to overcome the system losses between the points. In the conventional magnetron with a closed circle of cavity resonators, each cavity resonator is equally coupled to the adjacent resonators on either side and the radio frequency output may be taken from any one of the identical resonators by an antenna loop or probe. Energy flows toward the output resonator from around the circle of resonators, the first in the series of resonators being conveniently adjacent the output resonator so that the mentioned feed back energy easily moves directly from the "output" to the "input" of the series of resonators and oscillations are sustained.

Now, according to an important feature of this invention, the feedback energy from the output resonator is reduced and controlled, or eliminated, and energy, from an outside source to be amplified, is fed into the input resonator. The efficiencies of the magnetron oscillator may now be realized in an amplifier.

The particular embodiment of this invention shown in the drawing comprises a spiral arrangement of cavity resonators about the tubular cathode 1 and the intervening coaxial interaction space 2. The anode structure may comprise a cylindrical block 3 of such metal as copper with a series of holes 4 drilled lengthwise of the block. Radial slots 5, also extending lengthwise of the block, are milled to communicate with each hole and the center bore, or interaction space, of the block. Finally, a rectangular helical cut 6 is made in the wall of the center bore, the depth of the cut, measured in a radial direction, being sufficient to reach to or beyond the outer extremities of the holes 4. It now appears that the anode structure contains a series of cavity resonators with slots helically disposed about the center bore; and that the number of resonators may be increased to any desired number merely by increasing

ing the number of helical convolutions about the center bore. To prevent field interactions between adjacent ends of the end-to-end resonators, an edge-wound metal strip 7 is formed and threaded into the helical cut. The inside diameter of the wound strip should substantially coincide with the bore diameter, and the outer edge of the strip should make at least radio frequency contact with the wall of the block.

The cathode 1 is an indirectly heated sleeve supported at opposite ends on lead-in conductors 8 and 9, and is exteriorly coated with electron emissive material. To confine emission to the spaces opposite the cavity slots, the coated material may be applied barber-pole fashion to the sleeve. Insulated end plates 10 and 11 are provided for establishing an electric field parallel to the magnetic field and axially to the cathode. The lead-in conductors 12 and 13 support the plates.

A second edgewound strip 14 is preferably inserted alongside the shield strip and is sufficiently rigid to be slidable as a unit lengthwise of the anode structure so that the spaces at the ends of the cavities may be adjusted. A dielectric rod 15 is connected to strip 14 and mounted on bellows through the envelope of the tube to effect sliding of the strip. A limited range of tuning may thus be effected.

The loops 16 and 17 are mounted, respectively, in the two end resonators and are coupled through coaxial lines 18 and 19 to input and output circuits.

Magnetic pole pieces 20 and 21 are arranged at the ends of the cathode to provide an axial magnetic field for causing the electrons to follow spiral paths.

To operate, a direct current voltage is applied between the cathode and anode and a direct current magnetic field is applied with poles at the ends of the cathode. The magnitudes of the electric and magnetic field are comparable to the fields that would be applied to a magnetron of corresponding radial dimensions to produce circuit electron trajectories in the anode-cathode space. Now, a potential gradient between end plate 10 and 11 will give axial velocity to the electrons and the value thereof may be adjusted so that the pitch of the spiral path will equal the mean pitch of the cavity resonator slots.

In operation, signals within the tunable range of the cavity resonators are applied to loop 16 in the lower end resonator. Bunching of the electrons in the electric and magnetic fields in the anode-cathode space immediately commences under the influence of the signal voltage. The resulting electron bunches and electromagnetic waves of signal frequency travel in helical paths past and through the successive cavity resonators toward the output resonator. The strength of the axial electric field between plates 10 and 11 must be adjusted with respect to that of the radial electric and magnetic fields so that the rotating space charge will take a helical turn with a velocity close to that of the travelling wave, and the direct-current to alternating-current transfer of energy continues until at the output cavity the travelling electromagnetic waves have attained the maximum values permissible within the structural and electrical parameters of the amplifier. High level radio frequency energy is removed by loop 17.

To prevent reflections from the output or end cavity resonator toward the input end and to minimize standing waves and the danger of radio frequency voltage breakdown, it is important that

the load be properly matched, as to impedance and Q, to the output cavity resonator. Local feedback between resonators must also be prevented, and when necessary, resistive losses may be introduced as by roughening or otherwise treating the surfaces of the resonators or by the selection of anode material having a somewhat lower specific conductance. With feedback kept below the level necessary for self support oscillations, the amplitude of the output voltage will faithfully follow the signals applied to the input resonator, and the over-all voltage gain may be limited only by the radio frequency insulation at and around the output resonator.

Positive regeneration may of course be employed to increase gain when desired. Feedback could be through any of the known transmission lines which could be adjusted for regulating amplitude and phase of the feedback energy.

While there has been described above the principles of this invention in connection with specific apparatus, it is to be clearly understood that this description is made only by way of example and not as a limitation to the scope of the invention.

What I claim is.

1. An electron discharge device for amplification of high frequency energy comprising an elongated electron emitting cathode, an anode including a plurality of cavity resonators located in helical formation about said cathode, said resonators being coupled together in series along said helical formation, means adjacent said cathode to produce a magnetic field axially of said source, plates insulated from said cathode and anode, positioned at the ends of said cathode to produce an electric field axially of said source whereby said electrons will follow helical paths about said source, and output coupling means for the resonator at one end of said helix.

2. An electron discharge device comprising an elongated electron emitting cathode electrode, an anode including a plurality of high frequency resonators located in a helical formation about said cathode electrode, said resonators being coupled together in series along said helical formation, means for producing a magnetic field through said device parallel to said cathode electrode, means for producing an electric potential field parallel to said cathode electrode whereby electrons from said cathode electrode traverse a spiral path parallel to said cathode electrode, and an output terminal coupled with one of said resonators.

3. An electron discharge device according to claim 2, wherein said means for producing an electric field comprise electrodes spaced from said anode at opposite ends thereof and coaxial with said cathode electrode.

4. An electron discharge device comprising an elongated electron emitting cathode, an anode including a plurality of high frequency resonators located in a helical formation about said cathode, longitudinal electric and magnetic fields producing means located adjacent said cathode to cause said electrons to follow helical paths thereabout, shielding means located between the turns of said helical formation of resonators for isolating high frequency fields in said resonators that are adjacent one another in separate turns of said helical formation of said resonators, and output coupling means coupled to one of said resonators.

5. An electron discharge device comprising an

elongated source of electrons, said source comprising a helical electron emitting element, a plurality of high frequency resonators located in a helical formation about said electron source, said helical formation being positioned in alignment with said helical electron emitting element, said resonators being coupled together in series along said helical formation and output coupling means coupled to one of said resonators.
